UNITED STATES PATENT OFFICE.

THOR MOELLER, OF, PERTH, NORTH DAKOTA.

CUSPIDOR.

1,174,083.

Specification of Letters Patent.

Patented Mar. 7, 1916.

Application filed November 29, 1915. Serial No. 64,059.

To all whom it may concern:

Be it known that I, THOR MOELLER, a citizen of the United States, residing at Perth, in the county of Towner and State of North Dakota, have invented a new and useful Cuspidor, of which the following is a specification.

The present invention appertains to cuspidors, and aims to provide a novel and improved device of that character.

It is the object of the invention to provide a cuspidor which is thoroughly sanitary in use, which is not liable to spill no matter how much the same is tilted, and which can be cleaned easily and thoroughly, the parts being readily separated so that the entire device can be thoroughly cleansed and rinsed.

It is also within the scope of the invention to provide a cuspidor of the nature indicated, which will be practical in its use, as well as being simple and inexpensive in construction and manufacture.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a central vertical section of the improved cuspidor. Fig. 2 is a horizontal section taken on the line 2—2 of Fig. 1.

In carrying out the invention, there is provided a spherical casing 1 constructed of any suitable material and embodying a hemi-spherical bottom section 2 flattened, as at 2^a, to set upon the floor or other surface, and said casing includes a hemi-spherical top section 3. The sections 2 and 3 have a lap joint 4 and may be slipped frictionally together, or may be threaded together, whichever is desired, in order that the sections may be readily separated for purpose 50 of cleaning the cuspidor. The upper section 3 has an upper central opening 5 and a dished funnel 6, said funnel being extended at its lower edge to provide an annular overhanging lip or flange 7 surrounding the 55 opening 5.

The casing 1 is provided throughout its

inner spherical surface with rounded depressions or recesses 8 in which anti-frictional balls 9 are seated, and said balls are held in place relative to the casing by a spherical ball cage 10 constructed of suitable material. Said ball cage 10 embodies a lower hemi-spherical section 11 and an upper hemi-spherical section 12, the edge of the section 11 having upstanding dowels 13 fitting in sockets or recesses 14 with which the lower edge of the section 12 is provided, so as to hold the sections 11 and 12 assembled. The cage 10 is provided throughout its surface with openings or apertures 15 having curved walls and receiving the balls 9 whereby said balls project slightly beyond the inner surface of the ball cage. The upper section 12 of the ball cage has an upper central opening 16 below the opening 5, and the upper edge of said section 12 fits against the lip 7 to hold the ball cage in proper position when the parts are assembled.

The receptacle 17 is of spherical shape and is mounted for rotation in all directions within the casing 1, said receptacle 17 being disposed snugly between the opposite balls 9, whereby the receptacle can turn in all directions. The receptacle 17 has an upper opening 18 normally below the opening 5, and the upper edge of the receptacle 17 is normally disposed under the upper edge of the ball cage and lip 7, which prevents anything from falling behind said receptacle.

In order to hold the receptacle in upright position at all times, without regard to the position of the casing 1, the bottom of the receptacle is weighted, and to this end, the bottom has a raised portion 19 within which is embedded the weight 20 which will hold the bottom of the receptacle lowermost at all times.

When the casing is upright, the cuspidor will serve its office in the ordinary manner, but should the cuspidor be knocked over or tilted, the casing being rolled over on one side, the contents of the cuspidor will not be spilled out. This is due to the provision of the receptacle 17 mounted for rotation in all directions within the casing, it being noted that when the casing is tilted, the receptacle 17 will remain upright and the opening 5 being brought to one side of the receptacle will cause said receptacle to form a closure for said opening, to prevent spilling.

The cuspidor can be readily cleaned, the parts of the casing being separated, which will separate the parts of the ball cage therewith, so that the receptacle can be 5 removed and emptied. The several parts can be thoroughly cleaned before they are again assembled, which provides for perfect sanitation.

The other advantages and attributes of 10 the present cuspidor will suggest themselves to those versed in the art, taken in connection with the foregoing and drawing.

Having thus described the invention, what is claimed as new is:

15 1. A cuspidor comprising a casing having an upper opening, and cavities throughout its inner surface, anti-frictional balls seated in said cavities, means for holding the balls seated in said cavities, and a spherical receptacle disposed between the opposite balls, said receptacle having an upper opening normally below the aforesaid opening and a weighted bottom to hold the receptacle upright.

20 2. A cuspidor embodying a casing having an upper opening, a spherical ball cage within said casing having an upper opening below the aforesaid opening and having apertures throughout its area, balls seated 25 against the casing and projecting through said apertures to be held in place by said cage, and a spherical receptacle disposed between the opposite balls and having a weighted bottom and an upper opening normally 30 below the first mentioned opening.

35 3. A cuspidor embodying a casing having an upper opening, a spherical ball cage within said casing having an upper opening below the aforesaid opening and having ap-

ertures throughout its area, balls seated 40 against the casing and projecting through said apertures to be held in place by said cage, and a spherical receptacle disposed between the opposite balls and having a weighted bottom and an upper opening normally 45 below the first mentioned opening, the casing having an annular overhanging lip surrounding its opening and engaging the upper edge of said ball cage to hold said cage in place.

50 4. A cuspidor comprising a spherical casing embodying detachable upper and lower sections, the lower section being flattened to set on a surface, the upper section having an opening and funnel, the lower edge of 55 said funnel being extended to provide an annular overhanging lip surrounding said opening, the inner spherical surface of the casing being provided with rounded cavities throughout, anti-friction balls seated in 60 said cavities, a spherical ball cage embodying upper and lower detachable sections, the ball cage having apertures through which said balls project to hold said balls in place, the upper section of the ball cage having 65 an opening below the aforesaid opening and the upper edge of said section fitting under said lip to hold the ball cage in place, and a spherical receptacle between the opposite balls having an upper opening and a 70 weighted bottom.

In testimony that I claim the foregoing as my own, I have hereto affixed my signature in the presence of two witnesses.

THOR MOELLER.
